UNITED STATES PATENT OFFICE.

FRANK H. KEYS, OF COUNCIL BLUFFS, IOWA.

FASTENING DEVICE.

No. 851,173.

Specification of Letters Patent.

Patented April 23, 1907.

Application filed April 21, 1903. Serial No. 153,685.

To all whom it may concern:

Be it known that I, FRANK H. KEYS, residing at Council Bluffs, in the county of Pottawattamie and State of Iowa, have invented 5 certain useful Improvements in Fastening Devices; and I do hereby declare that the following is a full, clear, and exact description thereof, such as will enable others skilled in the art to which it appertains to make and 10 use the same, reference being had to the accompanying drawings, which form a part of this specification.

This invention relates to a fastening device.

The object of my invention is to provide a 15 fastening device adapted to be used in securing a curtain to a buggy top, the tent flap to a tent and be used in connection with garments and horse blankets and in fact wherever it is desirable to detachably secure two 20 pliable members.

In the accompanying drawings I have shown in Figure 1 an elevation of a carriage curtain secured to a top by means of my device. Fig. 2 shows a bottom view of my fastening. Fig. 3 shows a central sectional view thereof, while Fig. 4 shows a modification in which I employ a flat eye.

In carrying out my invention I use an annulus preferably in the form of a dished 30 ring which may be plain as indicated in Figs. 1 and 4 or be suitably embellished, and extending from this annulus 2 are two ears 3 projecting from the inner edge as shown in Fig. 2 while projecting from the outer edge as 35 disclosed in Fig. 2 are the four pins 1.

Held within the annulus 2 is a wire hook made of one piece of metal comprising the circular members 4 and the hook 5 and this wire is snugly held within the dish of the annulus which, however, at one point has a portion removed as shown in Fig. 3 to permit the hook 5 to extend beyond the same. The ears 3 are used in securing the hook members 4 within the annulus as shown. 45 Used in connection with this hook is an eye composed of an annulus 2' provided with the inward extending ears 3 and the projecting pins 1 and within this dished annulus are held the members 6 of the eye 7, this annulus 50 also being slightly cut away at a point to permit the passage of the eye 7 as indicated in Fig. 2.

The distance between the hook and the upper edge of the annulus 2 is a little less than 55 the diameter of the wire of the eye 7 as is indicated at z in Fig. 3 so that in order to se-

cure the eye below the hook the hook must be sprung up to permit the passage of the eye which finally finds a seating within the crook of the hook as is shown in Fig. 3 and this eye 60 can only be removed in forcing the same between the rounded edge of the annulus 2 and the hook 5. These fastening members are secured by forcing the pins through the fabric leather or other material to which they are secured and the pins are then bent over to secure the same. By this means I provide a fastening device which is exceedingly strong and can be used in connection with thin fabrics as the pin points are so far apart that the fabric 65 is not easily torn so that this device will stand a great strain especially adapting the same to be used on buggy curtains and to be used on tent flaps, horse blankets and the like.

Where the eye is to be hidden the same 70 may be used in the form of a flat plate as is shown at 8 in Fig. 4 provided with the projecting pin points 10 and the slot 9 adapted to accommodate the hook 5.

This fastener may be made of various sizes 75 and could also be made small enough to be used as a glove or shoe fastener and

Having thus described my said invention what I claim as new and desire to secure by United States Letters Patent, is,

1. A fastening of the character described including two members, one member being annular and provided with a peripheral wall cut away at one point and also having attaching prongs, a wire member bent upon 90 itself intermediate its ends and having a portion lying adjacent one face of said annular member and within said peripheral wall and also having a portion projecting through said cut away portion of the wall and directed 95 downwardly and upwardly to form a seat and then bent inwardly and outwardly over said annular member to form a fastening hook, the portion of the hook immediately adjacent said seat lying close to the annular 100 member to form a yieldable passage to said seat and the other of said two members having an eye adapted to be sprung between the first annular member and said hook into detachable engagement with said seat.

2. A fastening of the character described including two members, one member being annular and provided with a peripheral wall cut away at one point and also having attaching prongs, a wire member bent upon 110 itself intermediate its ends and having a portion lying within said peripheral wall and an-

other portion projecting through said cut away portion of the wall, the projecting portion immediately adjacent said annular member being formed into a seat and terminating in a hook member at its free end, and the other of said two members having an eye for detachable engagement in said seat, the first mentioned annular member forming the back of the seat for cooperation with said hook to prevent accidental disconnection of the two members.

3. A fastening of the character described including two members, a wire member engaged with one of the said two members, said wire member being bent intermediate its

ends to form a seat and a hook portion, and the other of said two members having an eye for detachable engagement with said seat, the edge of the first mentioned one of the two members adjacent said seat cooperating with the hook portion of said wire member to prevent accidental displacement of the eye with respect to its seat.

In testimony whereof I affix my signature in presence of two witnesses.

FRANK H. KEYS.
